(57) **CLAIM**

The ornamental design for a TV receiver, as shown and described.

DESCRIPTION

FIG. 1 is a front, right side, perspective view of a TV receiver showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the sound reflector which is slid-down thereof;

FIG. 9 is a cross-section of the 1-1 line in FIG. 1 thereof;

FIG. 10 is a front, right side, perspective view with the slid-up sound reflector thereof;

FIG. 11 is a front view with the slid-up sound reflector thereof;

FIG. 12 is a rear view with the slid-up sound reflector thereof;

FIG. 13 is a left side view with the slid-up sound reflector thereof;

FIG. 14 is a right side view with the slid-up sound reflector thereof;

FIG. 15 is a top view with the slid-up sound reflector thereof;

FIG. 16 is a bottom view with the slid-up sound reflector thereof;

FIG. 17 is an enlarged view of the sound reflector which is slid-up thereof; and,

FIG. 18 is a cross-section of the 2-2 line in FIG. 10 thereof. The broken lines indicate unclaimed portion of the article that form no part of the claimed design, and the dash-dot broken lines define the bounds of the claimed design and form no part of the claimed design.

1 Claim, 10 Drawing Sheets
